OWEN M. DE MUNNICK, OF NEW YORK, N. Y.

SAFETY DEVICE FOR RAILROAD-TRAINS.

1,140,580.

Specification of Letters Patent. Patented May 25, 1915.

Application filed January 11, 1913. Serial No. 741,394.

To all whom it may concern:

Be it known that I, OWEN M. DE MUNNICK, a citizen of the Netherlands, and a resident of the borough of Brooklyn, county of Kings, and city and State of New York, have invented a new and useful Improvement in Safety Devices for Railroad-Trains, of which the following is a specification.

The invention relates to that class of safety devices which is adapted to prevent accidents resulting from trains running past danger signals. Devices of this nature are as a rule provided with mechanisms controlled by the tower man and operated by the signal which he sets and result when the train passes a signal set at danger in closing the steam valve and opening an emergency air brake valve. Incidentally they frequently operate audible signals such as a bell and in some cases the sanding device and other similar auxiliaries connected with the stopping of trains are caused to function. One of the main defects resulting from the use of such means has been that the train came to a stop too rapidly so that the emergency brake becomes more of a menace than a remedy. Another defect has been when mechanical appliances are used that the necessity for operating them is so rare that they are likely to be out of order at the very time when they should be in reliable working operation. When electrical devices have been used the consumption of current in using batteries has proved a serious drawback.

The means used in my invention are such that they are reliable at all times and that they will cause the brakes to be set in stages rather than suddenly so that the train will be brought to a stop without a great jar which follows the sudden application of an emergency air brake.

The invention is illustrated in the accompanying drawing in which—

Figure 1 is a diagrammatic view of the system, and Fig. 2 is a general view illustrating the connections between the train and the signaling device.

In the drawings S is the railroad track and K the signal operated by means of a chain L or other equivalent device. The chain L is shown as operating the switch M, the function of which is to bring about a metallic connection by means of the wires P and O with the track S and the auxiliary

or third rail E. No batteries are used in this connection S P M O E, but when the danger signal is set the main rail and third rail are in condition to become part of an electric circuit of which the train furnishes the energy. Somewhere on the train, for instance on the tender, there is mounted a small electric dynamo D, which is driven by one of the axles in the same way as the dynamos for lighting railroad carriages are operated. The dynamo D is shown as series wound and communicating by connection H with one of the wheels F of the train. The dynamo is also electrically connected by means of the electric connection U with operating devices A B and C which are respectively shown as being the steam supply valve, the air brake valve and the warning bell. The electric connection continues through these operating devices to the shoe G which is attached to the car in any ordinary manner.

It will be seen that in the ordinary running of the train the dynamo although it continuously revolves and is thus maintained in operative condition does no work because its circuit is not complete. It is not until the shoe G comes into contact with the third rail E that the electric current flows through the connection H and U. In running past signals not set at danger, the shoe G will come into contact with the third rail E but the switch M being open there is no metallic contact between the main rail S and the third rail E so that there will be no consumption of electric energy. When however the signal K is set at danger and the switch M closes, the electric connection will be complete as soon as the shoe G comes into contact with the rail E and the operating device A B and C will immediately become active.

The third rail E if composed of a single rail would tend to throw on the full power of the dynamo and bring the train to a sudden emergency stop. In order to overcome the dangers of such a construction the third rail of my invention is constituted of a series of disconnected metallic rails. Five of such pieces 1, 2, 3, 4 and 5 are shown in the drawing although three pieces are ample for the ordinary system. Five pieces are used to adapt the third rail for use in both directions on a single track road, the function of the pieces 4 and 5 being the same as the function of the pieces 1 and 2 for trains

going in opposite directions. The rail pieces 1, 2 and 3 are insulated from each other, the insulating body being designated as I. The resistance R is used to connect each section with the adjacent section. The length of each section depends upon the highest speed at which trains ordinarily travel at that part of the road equipped with the third rail system. For ordinary use a third rail of three hundred to four hundred yards length will be ample whereas for express trains a third rail of perhaps one thousand yards in length might have to be used.

The function of the insulation I and resistance R is the following: Suppose the signal K to be set at danger and the train about to run past the signal, the shoe G contacts with the third rail section 1, electric energy from the dynamo will be promptly communicated to the operating devices A B and C, but by reason of the two resistances R that must be passed through before the electric connection with the conductor O attached to section 3 of the third rail is complete, the dynamo energy is kept relatively low and both the brakes are partially set and tend to slow the train. They do not bring it to a sudden stop. As the train runs on at somewhat reduced speed, section 2 of the third rail is reached by the shoe G. The train already tends to slow down and the dynamo revolves at a less rate of speed than before. At this point the shoe having passed over the first resistance R, there remains only one resistance in the circuit whose energy would be accordingly increased causing further application of the brake. When the last resistance R is passed the train is already in the process of slowing down considerably, the dynamo revolves at considerable less speed, but now the full current is permitted to take effect and the brakes are set in their maximum position so that the train must come to a stop. The stop is not a sudden one however because the speed of the train has already been considerably checked in passing over sections 1 and 2 of the third rail. The arrangement can be such that the train must come to a stop during the time that the shoe G is in contact with section 3 of the third rail although this is not necessary especially in view of the additional circuit V shown in Fig. 2. This circuit is completed by the electric switch N which operates when the maximum current is passing through its coil so that the circuit V is not completed until the shoe G has reached section 3 of the third rail. Once the circuit V is completed the dynamo current will pass through the brake coils independently of the track and third rail circuit so that the brakes will remain set even if the train should run beyond the third rail or until the dynamo itself ceases to rotate entirely. The main

rail S, or at least the sections which are in the neighborhood of the third rail must of course be metallically connected, as for instance, by the connection T. The arrows X and Y indicate the direction of the trains. When the trains come in the direction of the arrow Y the third rail sections 5 and 4 play the same part as do the sections 1 and 2 when the train comes in the direction of the arrow X.

The bell C circuit is shown as a branch circuit and it is obvious that a main circuit might be used for one or more main or branch circuits as are requisite to bring the train to a stop. The operating devices A and B are shown as brought into play by means of induced magnetism of the coil controlling their levers but any other devices may be substituted to take advantage of the available electric current.

Section 3 of the third rail is shown as of greater length than sections 1 and 2, but the length of these sections as well as the length of the entire rail and the number of resistances used will of course depend upon the particular conditions prevailing at the particular place where the signal is located. It is also obvious that the system is equally as applicable to steam railroads as to electric trains being independent of the motive power of the traction system as such.

What I claim is:

1. In a device for automatically stopping trains the combination of a main track and a regulating apparatus consisting of a third rail of a predetermined limited length extending over a short distance near signal locations, composed of sections insulated from each other and connected in series by means of resistances, a connecting circuit capable of conducting current between said regulating apparatus and the main track, and a switch for closing said connecting circuit.

2. In a device for automatically stopping trains the combination with a block signal of a main track and a regulating apparatus consisting of a third rail of predetermined limited length extending over a short distance near the signal location, composed of sections insulated from each other and connected in series by means of resistances, a connecting circuit capable of conducting current between one of the sections of said regulating apparatus and the main track and a switch interposed in said connecting circuit adapted to complete the metallic connection therein when the block signal is set at danger.

3. In a device for automatically stopping trains the combination of a main track and a regulating apparatus consisting of a third rail of predetermined limited length extending over a short distance near signal locations, composed of sections insulated from

- each other and connected in series by means of resistances, a connecting circuit capable of conducting current between said regulating apparatus and the main track, a dynamo 5 operated by the movement of the train, electric connections between said dynamo and the train wheel, operating devices to check the movement of the train terminating in a contact device for the regulating apparatus 10 and an electric connection between the dynamo and said operating devices whereby the current is adapted to operate the operating device.
4. In a device for automatically stopping 15 trains the combination of a main track and a third rail composed of sections insulated from each other and connected in series by means of resistances, a conductor capable of conducting current between said third rail 20 and the main track, a dynamo operated by the movement of the train, electric connections between said dynamo and the train wheel, operating devices to check the movement of the train terminating in a contact 25 device for the third rail, an electric connection between the dynamo and said operating devices and an additional circuit line adapted to complete the circuit through said operating devices and means controlled by 30 said electrical connections for automatically switching in said additional circuit line when the contact device reaches a predetermined section of the third rail.
5. In a device for automatically stopping 35 trains the combination with a block signal of a main track, a third rail composed of sections insulated from each other, resist-

ance for connecting said insulated sections in series, an electrical connection between the main track and said third rail, there 40 being a plurality of sections between the end of the third rail and the point at which said circuit is connected thereto, a switch in said connection controlled by said block signal and adapted to be closed when the signal is 45 set at danger, a source of current carried by the train, electrical connections from the source of current to the train wheel and to a shoe adapted to contact with said third rail, brake controlling means in the said connections 50 whereby when said block signal switch is closed and the shoe is in contact with the third rail, current will flow through the circuit and operate the brake controlling means, the strength of the current varying 55 with the distance the shoe has advanced along the third rail and an auxiliary connection between said wheel and shoe and means controlled by current in the circuit whereby the auxiliary connection is adapted to be closed when said shoe has advanced 60 along the third rail to the section of least resistance, whereby said brake controlling means will continue to be operated independently of the third rail and the block 65 signal circuit.

In testimony whereof I have hereunto set my hand in the presence of two subscribing witnesses.

OWEN M. DE MUNNICK.
